UNITED STATES PATENT OFFICE.

GEORGE EDWARD NYE, OF BRISTOL, PENNSYLVANIA, ASSIGNOR OF ONE-HALF TO EDWARD TREDICK, OF SAME PLACE.

THREAD-FEEDING MECHANISM FOR KNITTING-MACHINES.

SPECIFICATION forming part of Letters Patent No. 392,685, dated November 13, 1888.

Application filed April 19, 1887. Serial No. 235,329. (No model.)

To all whom it may concern:

Be it known that I, GEORGE EDWARD NYE, of Bristol, in the county of Bucks and State of Pennsylvania, have invented certain Improvements in Thread-Feeding Mechanism for Knitting - Machines, of which the following is a specification.

The aim of my invention is to provide a machine adapted to give stockings or other articles produced therein an increased thickness at the ends or other required points by introducing into the fabric at such points and not elsewhere an extra thread in addition to the thread commonly used, the two threads being combined and introduced as one. To this end I combine with any ordinary knitting mechanism a guide through which the secondary thread is introduced at the side of the primary thread, so as to pass to the needles therewith, a device to stop the delivery of the secondary thread during the formation of those parts of the fabric in which it is not required, and automatic devices for throwing this stop into and out of action at the proper times.

My invention resides in the peculiar construction and combination of these supplemental parts, as hereinafter recited in detail.

For the purpose of illustration I have shown my improvement applied to a cylinder knitting-machine which is in other respects identical, or practically so, with that shown in Letters Patent of the United States, granted to me on the 28th day of April, 1885, No. 316,907.

In the accompanying drawings, Figure 1 represents a top plan view of the machine. Fig. 2 is a side elevation of the same. Fig. 3 is a vertical cross-section on the line $x-x$ of Fig. 1.

In the drawings, A represents the frame of the machine; B, the rotary cylinder, in which the vertical needles 1 are mounted; C, the dial-plate, in which the horizontal needles 2 are mounted, and D the cam-cylinder.

The foregoing parts are constructed and arranged to operate in connection with the driving devices, needle-actuating cams, and other customary parts of the machine in essentially the same manner as in the patent above referred to.

In applying my improvement I fix in posi-

tion at the side of the cylinder a stationary thread-guiding plate, D, provided with an opening, a, through which the customary thread is delivered, and by which it is presented in position to be grasped by the vertical needles in the usual manner.

In addition to the primary thread, E, which forms the body of the fabric, I provide a secondary or supplemental thread, F, which is drawn from a spool or bobbin, O, and conducted through guides of any suitable character into the guide D in contact with the primary thread, so that the primary thread in advancing to the needles will act with frictional effect on the secondary thread and tend to carry the latter forward therewith. When the secondary thread is left free, it will pass inward in company with the primary thread, and, united therewith, the two will be knitted as one thread into the garment, which is consequently made of double thickness and strength.

In order to prevent the feeding of the secondary thread into any other than the required portions of the garment, I provide the stop or clamp, consisting of the stationary jaw G and the clamping-lever H, pivoted thereto.

The secondary thread is carried between these two parts, so that when the lever is properly actuated the thread will be pinched fast between them and prevented from advancing, whereupon the strain thereon will have the effect of breaking it inside of the thread-guide or between the guide and the needles, leaving the end of the secondary thread in contact with the other.

The secondary thread, thus broken, remains at rest, while the primary thread continues its advance until the clamp is opened, whereupon the secondary thread, thus set free, is again drawn forward by the primary thread, with which its end remains constantly in contact.

The clamping-lever is connected by a link, b, to an elbow-lever, e, which is pivoted to the main frame and subjected to the action of a spring, d, which urges it backward, and a pattern-chain, e, which at the proper time urges it forward.

The pattern-chain is mounted on a roll, f, journaled in the main frame and actuated through a ratchet-wheel, f', on its end by a pawl-carry-

ing lever, *g*, pivoted to the main frame. The lever is acted upon by a spring, *h*, and moved at the proper intervals to advance the pattern-chain by one or more cams, *i*, carried by 5 an arm depending from the cylinder. This mechanism for moving the pattern-chain is identical with that in the patent before al-luded to, except that, in place of the single cam of the patent, there are, as shown in the draw-10 ings, two oppositely-placed cams, *i*, to effect the advance of the pattern-chain at each semi-rotation of the cylinder. By varying the style of the chain the clamp may be caused to de-liver the secondary thread continuously into 15 the fabric through a number of successive courses, in which case the stocking or other article will be thickened around its entire circumference; or the chain may be so formed that it will deliver the secondary thread into 20 the successive courses but part way round.

In the drawings I have shown a chain adapted, when moved, at each half-rotation of the needle-cylinder to produce this latter ac-tion, the effect of which will be to thicken the 25 stocking on the front side of the knee only by introducing the secondary thread into the suc-cessive courses in short lengths, in a manner which will be more fully understood on refer-ence to my application for improved stocking 30 filed March 17, 1887, Serial 231,313.

In order that the secondary thread may be relieved from all tension and resistance at the time it is to be started again into the fabric, I prefer to use slackening devices, such as 35 shown in the drawings; but it is to be under-stood that these are not a necessary feature of my invention.

The slackening device, as shown, consists of a vertically-reciprocating arm, *J*, through an 40 eye on which the secondary thread passes be-tween the clamp and the stationary guide *K*. The lower end of the arm *J* is connected to a lever, *L*, pivoted on the main frame, depressed by a spring, *M*, and lifted at proper intervals 45 by a cam, *N*.

While the clamp is holding the secondary thread so that it cannot be drawn backward out of the guide *D*, the bar *J* rises and draws additional thread from the spool, and before 50 the clamp is released the arm *J* descends, and thus slackens the thread, so that the slackened end may pass freely into the fabric. This in-sures the advancement of the secondary thread by the other, the friction of the primary thread 55 being sufficient in all cases to advance the slack-enend thread.

Having thus described my invention, what I claim is—

1. The rotary cylinder, its needles, and the cam-cylinder, as usual, in combination with 60 the fixed guide *D*, adapted for the passage of two threads in contact with each other to the needles, the jaw *G* and lever *H* to control the advance of one thread, the elbow-lever con-nected to the clamping-lever, the pattern-chain 65 and spring to actuate lever *c*, the chain-carry-ing roll, the ratchet mechanism for turning the roll, and one or more cams, *i*, movable with the cylinder to actuate the ratchet mech-anism, whereby a supplémental thread may 70 be laid into the fabric with the main thread intermittingly and at predetermined times.

2. In combination with the needle-cylinder, its needles, and the cam-cylinder, as usual in cyl-inder knitting machines, the stationary guide 75 *D*, adapted for the passage of two threads there-through, the clamp *G H*, to control one of said threads, the lever *c*, a suitable connection thence to the clamp-lever *H*, spring *d*, and pattern-chain *e*, to control said clamp, mech-anism for advancing the pattern-chain, the 80 vertically-movable slack-arm *J*, and the cam *N* on the needle-cylinder to actuate said arm, whereby a supplemental thread laid into the fabric by and with the main thread may be bro-85 ken at intervals and slackened at the proper time to insure its advance.

3. In a cylinder knitting machine, the nee-dle-cylinder, its needles, and the cam-cylin-der, as usual, in combination with the fixed 90 guide *D*, adapted for the passage of two threads, the jaw *G* and lever *H*, to clamp one thread, the lever *c*, the link or connection from the lever *c* to the clamping-lever, and spring *d*, to 95 operate the clamp-lever, the pattern-chain *e*, its sustaining-roll, the ratchet mechanism to turn the roll, the cam or cams *i* on the cyl-in-der to actuate the ratchet mechanism, the ver-tically-movable slack-arm *J*, and the cam *N* on the cylinder to actuate said arm, whereby 100 a supplemental thread may be laid intermit-tingly into the fabric subject to the control of cams *i* and *N*.

In testimony whereof I hereunto set my hand, this 2d day of March, 1887, in the presence of 105 two attesting witnesses.

GEORGE EDWARD NYE.
